UNITED STATES PATENT OFFICE.

GEORGE B. BREAKY, OF NEW YORK, N. Y., ASSIGNOR TO HERRMANN & GRACE COMPANY, OF BROOKLYN, NEW YORK, A CORPORATION OF NEW YORK.

METALLIC DOOR.

§17,366.

Specification of Letters Patent. Patented Nov. 29, 1910.

Application filed April 28, 1909. Serial No. 492,723.

To all whom it may concern:

Be it known that I, GEORGE B. BREAKY, a citizen of the United States, and a resident of Kings county, borough of Brooklyn, city and State of New York, have invented certain new and useful Improvements in Metallic Doors, of which the following is a specification.

My invention relates to metallic doors in the art of building construction and has for its object to produce a door substantially of metal throughout, the constituent parts of which shall be of materials easily obtained from stock and easily assembled in the completed structure without the use of other than ordinary and inexpensive tools.

A further object of my invention is to produce such a door which, either by itself or combined with other fire-proof materials, shall resist combustion and the passage of flame and hot gases across or through its plane.

A further object of my invention is to produce a metallic door which shall be to a very considerable extent sound proof.

A further object of my invention is to produce a metallic door, the resonant qualities of which are substantially suppressed so that the metallic clang characteristic of many metallic doors when struck or forcibly opened or closed may be absent.

A still further object of my invention is to provide a door which shall be easily and quickly assembled with a minimum of skilled labor, shall present few seams, screws or other openable points to be attacked either by man or the elements, shall have a maximum of rigidity and stiffness with a minimum number of parts, shall retain its shape and stiffness without warping under all conditions of temperature and moisture and, at the same time, shall be ornamental and neat in appearance and simulate very perfectly the conventional wooden doors of commerce which my improved door is designed to replace.

The scope and character of my invention may be more easily understood by reference to the specification following and to the drawings accompanying, in which—

Figure 1 is an elevation, taken from one side, of a preferred form of my improved door, the molding being broken away at one corner of the panel; Fig. 2 is a plan view, taken from above, of Fig. 1; Fig. 3 is an

enlarged vertical section through the top rail of my door along the line 3—3 of Fig. 1, the lower part of the section being broken away; Fig. 4 is a similar section, also broken away, taken along the line 4—4 of Fig. 1; Fig. 5 is a similar horizontal section, also broken away, taken through the stile of my door along the line 5—5 of Fig. 1; Fig. 6 is a similar section, also broken away, taken along the line 6—6 of Fig. 1, but including both stile and rail; Fig. 7 is a greatly enlarged detail of part of Fig. 5 bringing out the molding only and its fastening clip as shown in Fig. 5, and Fig. 8 is a perspective view of the clip used to fasten the panel molding as shown in section in Figs. 5 and 7.

Briefly, I construct my door by taking two identical sheets of metal, of area substantially that of the finished door, superposing one sheet upon the other but separated therefrom by distance pieces placed at suitable points, preferably at the edge and around that portion which is to become the panel of the completed door, and then slipping over each longer edge of the door a stile thicker than the combined first sheets, said stile being bent up from sheet metal so as to embrace said pair of first sheets. Each stile is riveted at suitable points to the panel sheets after which top and bottom rails similar in formation to the stiles are slipped into place and also riveted; suitable provision is made for jointing and fastening stiles and rails together where they abut. Lateral tongues thrown out from the panel sheets on each side and around the edge of said sheets serve to maintain the panel sheets centrally as to stiles and rails and a suitable molding is finally placed on each side of the door to fill and cover the junction of panel sheets with rails and stiles.

Referring to the drawings in detail, A, A' are panel sheets of metal, preferably of iron or steel and of suitable thickness, say about $\frac{1}{16}$ gage; these sheets are identical in size and are cut rectangularly to substantially the area of the finished door. One of these panel sheets is then superposed upon the other but separated uniformly therefrom, say at a distance of about $\frac{1}{8}$ inch, by suitable distance pieces. Preferably these distance pieces take the form of channel irons B placed around the entire edge of the panel sheets, and bars C placed parallel to the outer distance pieces but nearer to the center

of the door, these last named distance pieces C corresponding substantially with the shape and size of the finished center panel D of the completed door. Suitable rivets a, b, 5 passing through distance pieces and panel sheets hold the structure together.

The stiles E, E', and rails F, F', are each formed preferably of a single piece of sheet metal, usually of the same thickness as the 10 panel sheets and to the shape shown in the figures, that is, there is an edge section c, substantially wider than the combined thickness of the arranged panel sheets, having side sections d, d, extending therefrom parallel to the plane of the door and toward the center thereof, each of these side pieces having sections e, e, bent at right angles thereto and toward one another, said last named sections being finally again bent parallel to the panel sheets and to one another to form flanges f, f. The distance between these last sections f, f, is determined to just equal the thickness of the combined panel sheets.

25 The flange sections f may or may not be cut away on the stiles at a distance from the top and bottom of the door substantially equal to the width (without flanges) of the end rails (see Fig. 1), and the same flange sections of the rails are similarly cut away to clear the stiles. The stiles also are extended from the top to the bottom of the door, the rails being shorter than the door is wide by the combined width (without flanges) of the two stiles, the rails and stiles thus fitting together by a square joint rather than by a miter joint. Each stile and rail is, hence, seen to be of shape somewhat like a long box, open at the ends, and having a 30 longitudinal central opening along one edge adapted to slip over and embrace the combined panel sheets.

To maintain the panel sheets centrally of the rails and stiles, opposite tongues G are 45 thrown out at right angles to its plane from each panel sheet, the length of these tongues being sufficient to just contact with the internal surfaces of said rails and stiles when the combined panel sheets are central.

50 Rails and stiles, when slipped over the edges of the panel sheets, are pushed inwardly until the inner surfaces of their edge sections e are in contact with the outer edges of the panel sheets A A' when they are fastened in place by the rivets b which pass through the flanges f of the panel sheets and the distance pieces C.

At each corner of my door the top or bottom rail, as the case may be, will abut 60 upon the stiles as previously stated. To insure a permanent and suitable joint at these abutting points, I take a short piece of angle iron g (the length of which is about equal to or a trifle less than the width of the rail proper) and rivet one leg h of said angle

at i to the inwardly turned section e of the adjoining stile; the angle is so set that the remaining leg h' has its face parallel to and within the outer surface of stile sections d by a distance equal to the thickness of the 70 same sections d of the rail. These rail sections d are then, at each end, cut so as to lie upon the legs h' to which they are permanently fixed by screws j. The angles g must, of course, be attached to the stiles before the top and bottom rails are put in place.

The edge sections c of both top and bottom rails are prolonged at each end, beyond the side sections d, as tongues k fitted to 80 closely engage the inner surfaces of the open ends of the two stiles where they are supported upon angles l to which they are secured by screws m. Each angle iron has a length somewhat less than the width of the 85 stile and is fixed to the panel sheets within the open end of each stile by one or more of the outer rivets a which also hold said panel sheets together and against the channel iron B.

90 After the panel sheets, stiles and rails have been firmly and permanently assembled as aforesaid, I complete my door by placing a molding H in the angle n where the flanges f are joined to the panel sheets. This molding may be formed of sheet metal of any convenient thickness; its section, also, preferably as shown in the figures, need not necessarily be as there shown but may have any form which taste may suggest provided only that there be the downwardly projecting portions o and p, the former adapted to engage the resilient curve q and the latter adapted to be fastened to the upturned section r by the rivet s.

100 The resilient curve q and upturned section r are formed upon a clip or angle piece made of sheet metal of convenient thickness either by hand or, preferably, pressed out by means of a punch and die. Each of these 110 clips is about $\frac{3}{8}$ " wide and one is placed every 12" or so along the border of the center panel D in the angle n on each side of the door, being held in place by certain of the rivets b used for attaching stiles and 115 rails to the panel sheets. One leg of each clip has a depressed portion q formed in it and upon the molding H there are formed similar depressions u adapted to seat themselves in the aforesaid depressions q the depressions u being spaced along the molding 120 to correspond with the locations of the clips. The other leg of each clip is formed, also preferably by use of punch and die, so as to have a tongue r and the upturned end r, 125 the tongue r being convexed toward the panel sheets and preferably to contact therewith. The purpose of this convexing is two fold: First, by beginning the convex at the edge x of the flange f the clip is steadied 130

upon the flange and any rotation upon the rivet *b* is precluded and, second, when its end *y*, which should lie just inside the upturned end *r* so as to serve as an abutment 5 against which the rivet *s* may be upset from without, is forcibly impacted by the operation of such upsetting, there will be no yielding since the effective impact will be all exerted downward against the rigid panel 10 sheets.

To fix the molding in place, it is only necessary to bring its downwardly projecting section *o* against the inwardly turned section *e* of rail or stile and to press the 15 molding toward the panel sheets; by reason of the resiliency of the clip leg in which is the depression *q* said leg will give and allow the depressions *u* of the molding to slip into the depressions *q* thus constituting the 20 means by which one side of the molding is retained. The other side of the molding is fixed permanently by rivets *s* passing through the sections *r* and *p* of clip and molding respectively.

25 My door as above described is very simple, comprising but a limited number of plain and substantial pieces which are easily formed of stock materials. There are substantially no screw or easily opened joints 30 on either side of the door and, being constructed of thin sheet metal, it is necessarily light and easily operated, while the distance pieces and form of the rails and stiles makes the structure very stiff.

35 My door is obviously fire proof but to retard the conduction of heat through its substance, I may inclose between the panel sheets, asbestos or substances of similar properties and in the form of sheets (plain or corrugated) as indicated at *I*; or such material may be in granulated, powdered or any other desired form. The empty spaces within the 40 stiles and rails may also be filled with asbestos or similar material in the same way as at *J*. It is not even necessary that such material should be strictly non-combustible *per se*, since confined in the door, as it is, the absence of oxygen would prevent ignition. Any non-conductor of heat therefore would 45 satisfy the fire proof qualities.

By the use of asbestos as above described, with its entrained air cells, my door would not only be substantially fire proof but would also be substantially sound proof; it would 50 also lack resonance and be dead and inert as a source of sound when slammed in opening or closing or if struck.

Many changes in detail might be made

without departing from the spirit of my invention which is embodied in the following 60 claims:

1. A metallic door comprising a pair of panel sheets; a pair of opposite hollow members having side and edge sections extending at least the full dimensions of the panel sheets and embracing the edges of said panel sheets, the inner surfaces of said edge sections along substantially their entire length being in contact with the edges of the panel sheets; a second pair of opposite hollow 65 members embracing remaining edges of said panel sheets and having side sections extending between the side sections of said first named pair and an edge section extending at least the full dimension of the panel sheets, the inner surfaces of said edge section along substantially its entire length being in contact with said panel sheet edges; rigid distance pieces attached to and between the panel sheets along each outer edge of said 70 sheets; rigid distance pieces attached to and between the panel sheets and the inner edges of the aforesaid hollow members along the entire length of said inner edges; tongues 75 extended outwardly from each edge of each panel sheet and contacted with the inner surface of the side sections of the hollow members; and inner strengthening angles joining adjacent ends of the hollow members together, as and for the purpose described. 80

2. A metallic door comprising a pair of panel sheets; pairs of opposite hollow members constituting stiles and rails embracing the edges of said panel sheets and having their edge sections in contact with the edges 85 of the panel sheets around the entire door; a rigid distance bar attached to and between the panel sheet edges around the entire door; a second inner distance bar between the panel sheets and around the entire door; 90 tongues extended outwardly from each edge of each panel sheet and contacted with the inner surfaces of the sides of the stiles and rails; molding attaching clips spaced around the door; and rivets which pass through 95 said molding attaching clips so as to pass through the panel sheet and the inner distance bar, as and for the purpose described.

In testimony whereof I have hereunto set my hand in the presence of two subscribing 100 witnesses.

GEORGE B. BREKEY.
